LAUNDRY WASHING MACHINES

Geoffrey Smith, Woodingdean, Sussex, England, assignor to Polymark (Holding) Limited
Filed Sept. 17, 1962, Ser. No. 223,891
Claims priority, application Great Britain, Sept. 21, 1961, 33,821/61
1 Claim. (Cl. 68—58)

The present invention relates to improvements in laundry washing machines, and it has for its object to provide a machine capable of carrying out washing and associated operations in such manner that articles being washed travel progressively relatively to the flow of washing medium but in the opposite direction, so that articles which have already been washed encounter the clean incoming medium and incoming articles encounter the washing medium which has already been in contact with a series of articles in preceding stages. It is to be understood that the references herein to "washing" include other similar operations such as hot or cold rinsing operations, hot treatment operations, such as are commonly referred to as boiling operations, and preliminary washing operations.

In accordance with the present invention a laundry washing machine comprises an inner cage rotatable within an outer cage in contact with a washing medium, the articles being caused to travel through the inner cage in the opposite direction to the flow of washing medium in the outer casing.

A washing medium may be admitted at one end and steam and/or detergent may be admitted at different points of the outer cage so that different regimes of operation are maintained in different sections of the inner cage through which the articles being washed are caused to pass in succession in transit from one end of the inner cage to the other.

If desired, additional quantities of washing medium are admitted to predetermined points of the outer cage intermediate the ends thereof to maintain predetermined liquid levels at various points of the outer cage, by-pass ducts being provided as required to assist in maintaining the required levels.

The inner cage is perforated and provided with a series of inwardly directed beaters to ensure that articles being washed are continuously agitated and maintained in circulation within the inner cage, such articles being lifted to a high level and then allowed to fall towards the lower part while the cage is in rotation.

Conveniently, the inner cage is provided with a series of scoops around its periphery, such scoops being arranged in a series of parallel peripheral rows so that liquid is caused to flow from the space within the outer cage into the inner cage to maintain an efficient washing action upon the articles.

The outer cage may be provided with a series of inwardly directed fin-like portions extending towards and nearly into contact with the inner cage so as to assist in providing separate zones where different operating regimes are maintained and to prevent the through flow of washing medium lengthwise of the outer cage and causing said washing medium to flow in successive paths into and out of the inner cage to maintain an efficient washing action on articles being treated.

The inner cage and the outer cage are preferably arranged at a small inclination to the horizontal so that the articles being treated tend to shift progressively along the inner cage from one end to the other.

The equipment may include a drying section for articles leaving the final washing stage, said drying section being provided either by an integral part of the inner cage,

through which hot air is circulated or a separate cage or centrifugal extractor to which the articles are supplied after leaving the aforesaid inner cage in which washing operations are effected.

Articles leaving the inner cage may fall into a section of the outer cage from which said articles are lifted out of the washing medium by means of an elevator conveyor, and said conveyor may be associated with a presser roller to eliminate surplus liquid.

An exemplary embodiment of the invention is shown by way of example on the accompanying drawings wherein:

FIG. 1 is a side elevation partly in section and in diagrammatic form of a laundry washing machine according to one embodiment of the invention.

FIG. 2 is a diagrammatic cross-section taken on the line II—II in FIG. 1, certain parts being omitted to show the main features more clearly.

FIGS. 3 to 5 illustrate details applicable to both embodiments of the invention; FIG. 3 being an enlarged detail in perspective showing the arrangement of the inner cage, the beaters on the inner wall thereof, the scoops on the outer wall thereof and optional fin-like divider rings associated with the outer cage,

FIG. 4 is a detail corresponding to FIG. 3 taken lengthwise of the beaters, and

FIG. 5 is a detail showing the mounting for the inner cage and including a sectional view through the beaters and the scoops.

In the embodiment of the invention illustrated on the accompanying drawings, the features of a laundry washing machine are shown comprising a closed liquid-holding outer cage 11 housing a relatively long perforated inner cage 12 rotatable within the cage 11 and in which various regimes of operation are maintained. A common feature in all the embodiments described is that articles to be washed are received at or near one end of the inner cage 12 and are moved progressively or step-by-step through this cage towards the other end, and at least the major part of the washing medium is admitted to the plant adjacent said other end of the inner cage while the spent washing medium is taken away adjacent the point where incoming articles are admitted to the inner cage.

The progressive movement of the articles being washed can be effected in various ways. In the embodiment of FIGS. 1 and 2 this displacement of the articles is obtained by the fact that the outer cage 11 and the inner cage 12 are both slightly inclined to the horizontal. In all cases the inner cage 12 is maintained in rotation and it may, if desired, be reversed in direction from time to time. During operation and while the inner cage 12 is in rotation, the latter contains articles at different positions of its length, which are being subjected to various regimes of operation, that is to say they are being subjected to various, and progressive, washing operations, and are moved progressively through the inner cage.

In the embodiment of FIGS. 1 and 2 a progressive and continuous movement of articles within the inner cage is obtained by the fact that the inner cage 12 and the outer cage 11 are slightly and adjustably inclined to the horizontal. This embodiment will now be described in greater detail.

As shown in FIG. 1 an outer cage 11 of substantially circular shape is supported on a frame member 15 which in turn is pivotally mounted at 16 on a ground support not separately shown but represented by the ground line 17, and a screw adjustment device 18 is provided to permit the inclination of the frame 15 to the horizontal to be adjusted. An additional support screw 19 may be provided at an intermediate point as shown. The inner

cake 12 is rotatably supported within the outer cage 11 by means of a series of adjustable support rollers 20 (see also FIG. 5) which engage smooth rings 21 on the inner cage 12. The rings 21 are disposed at each side of toothed ring members 22 which are arranged for engagement at the top of the outer cage 11 by driving pinions 23 carried by a shaft 24 driven by a motor 25 through a variable speed gearing 26 indicated in outline form. The support rollers 20 may, if desired, include an idler pinion 201 between them as shown in FIGS. 1 and 5 and lateral guidance may be obtained by a lateral guide roller 202 disposed on a nearly radial axis. The slight inclination to the true radial direction is such that the bearing faces are of slightly tapered form to secure good running properties.

It will be seen from FIG. 1 that several (three in the drawings) sets of rings 21, 22 are distributed along the length of the inner cage, each being supported by roller units 20, 201 on the two sides of the vertical central plane of the cages. One of such units on one side is provided with a lateral guide roller 202, while a corresponding unit on the other side of the axis may be provided with a similar guide roller on the other side of one of the ring groups 21, 22.

In all cases the liquid volume between the inner cage 12 and outer cage 11 is reduced to the minimum so that the washing medium is caused to travel through the inner cage rather than between the inner and outer cages, and his action may be assisted by the provision of ring members 52 as explained hereinafter. Furthermore, the roller support units 20, 201 (with roller 202 in some cases) may be housed in extension housings or "pods" 20a on the outer cage 11 as indicated on the drawings.

The peripheral walls of the inner cage 12 are perforated and said cage is provided internally with a series of V-shaped beaters 13. The side walls of these beaters are also perforated and there is a non-perforated lengthwise division member 27. The space within said beaters is furthermore divided into a number of separate sections by means of radial plates 28 shown on FIG. 4, extending at right angles to the division member 27.

Scoops 29 are attached to the outer wall of the inner cage 12 as shown in FIGS. 3 and 4, one set of scoops being conveniently arranged opposite each division member 27, while additional scoops may be provided on the peripheral sections between adjacent beaters 13. These scoops are arranged in a series of parallel zones around the container and each scoop comprises a box-like portion extending in both directions on the outer face of the cage 12, being supported by an extension portion 30 of the division member 27. It will be seen that on rotation of the inner cage 12 in one direction or the other, one or other of the projecting portions of each scoop tends to force the washing medium into the inner cage 12 and those scoops arranged near the beaters 13 cause a flow of liquid through the perforations in the beaters, all of the water streams so directed into the inner cage assisting in maintaining an efficient washing action upon the articles being treated.

This action upon the articles being washed will now be explained in more detail with reference to FIG. 2 of the drawings where it is assumed that the inner cage 12 is being rotated in the anti-clockwise direction with the beater 13 at the lowermost section of the inner cage 12 tending to lift a charge of articles initially in an upward path resting in the angle between one perforated side wall of the beater and the peripheral wall of the cage, and this charge of articles is thus carried upwardly almost to the top of the inner cage from which point they fall towards the lower part of the cage so that these articles are maintained in circulation in a path which may be somewhat indicated in full lines by the arrow 31 in FIG. 2.

The outer cage 11 contains washing medium to a predetermined level in the static state but, of course, this washing medium is maintained in continuous movement

by the rotation of the inner cage 12 so that at any particular moment only a fraction of the washing medium lies externally of the cage 12 since most of the liquid is caused to flow into and through the cage 12 partly by the rotation of said cage itself and partly by the action of the scoops 29 which maintain a flow of liquid inwardly of the cage 12 as indicated by the arrows 32 (FIG. 2), such inward movement of the liquid being effected through the peripheral walls of the cage 12 and also through the perforated leading faces of the beaters 13.

The inward movement of the washing medium acting on the batch of articles being carried upwardly in the angle between the rising beater 13 and the peripheral wall of the inner cage 12 helps in preventing the articles from being pressed against the walls of the cage and maintains an efficient washing action at every point of the movement of the articles during the washing operations.

In all cases the articles are moved lengthwise through the inner cage 12, this movement being in the opposite direction to the flow of washing medium through the plant. Thus, referring to FIG. 1 incoming articles are supplied on the conveyor 33 in a continuous flow and they then pass for example by means of the guide chute 34 into one end of the cage 12 which is provided with a feed opening 35 for this purpose.

Articles being washed and caused to travel through the inner cage 12 by reason of the inclination of the cages 11 and 12 as shown in FIG. 1, are removed from the inner cage 12 at the opposite end thereof in any convenient way. For this purpose and as indicated in FIG. 1 for example, the lower end of the outer cage 11 is provided with a well 37 near a delivery end opening 36 from the cage 12. A rising conveyor 38 extending out of this well receives the articles leaving the cage 12 through the opening 36 and carries the articles away for further treatment. If desired a presser roller 39 may be provided above the conveyor 38 to express surplus water from the articles, and there may be a plurality of such rollers 39 so that articles may be passed directly into a centrifuge or dryer, or, alternatively, the articles leaving the conveyor 38 may be handled in batches by one or more hydro-extractors. Such a centrifuge may be arranged co-axially of and in line with the inner cage 12 but in most cases it would rotate at a higher speed than the cage 12.

As already indicated, the washing medium flows in the opposite direction to the travel of articles through the inner cage 12, and for this purpose clean incoming washing medium is admitted through a pipe 41 to the end of the outer cage 11 from which the articles which have finished their treatment are withdrawn. As shown in FIG. 1 the inlet pipe 41 opens into the well 37 but it should be understood that this well forms an optional feature of the invention and when such a well is not provided the pipe 41 is connected directly to the corresponding end of the outer cage 11. The spent washing medium removed from the other end of the cage 11 near the feed opening 35 for the articles, is taken off through a pipe 42 as spent liquor.

It will be understood that a series of different washing regimes may be maintained in the different zones of the inner cage 12 and these may vary and may be varied to suit particular requirements. One example may comprise the following steps, counting from the inlet 35 to the outlet 36:

- (1) Cold washing operation.
- (2) Hot washing operation.
- (3) Boiling operation.
- (4) Hot rinse.
- (5) Cold rinse.

In order to maintain these different regimes of operation various additions may be made to the washing medium flowing through the outer cage 11. For example and as shown on FIG. 1, a steam supply pipe 43 may be

provided which embodies one or more delivery pipes 44 to admit steam at one or more points of the cage 11.

It will, of course, be understood that with this type of operation and with the equipment in continuous movement, it is difficult to say that the washing medium reaches any particular level in the outer cage 11 at any particular point because a large proportion of the washing medium is being circulated through the inner cage 12, which action is promoted by the action of the scoops 29 which maintain a substantial proportion of the liquid in movement from the upper part of the inner cage 12 to the lower part thereof. Nevertheless, it may be found that a greater proportion of washing medium collects in certain zones of the outer cage 11 than is required for operation in that section of the equipment, while other parts of the inner cage 12 may be short of washing medium, and for this purpose a by-pass pipe 48 may be provided for collecting liquid from a higher level and returning it to a lower level, or a series of such pipes may be provided as required to maintain the proper amounts of liquid at various points of the inner cage 12.

Conveniently the washing medium admitted at the pipe 41 will comprise lime-free softened water so that the section towards the right-hand side of the outer cage 11 and inner cage 12 in FIG. 1 is effective for rinsing the articles completing the washing stages. In such case detergent media are added to the washing medium at any suitable point of the outer cage 11. Thus, for example, a detergent liquid or powder may be fed into the cage 11 by means of a feed pipe 50, as indicated on FIG. 1.

In many cases it may be desirable to provide means within the outer cage 11 which hinder the free flow of washing medium or water from one point to the other and to ensure that all this liquid passes through the inner cage 12. For this purpose and as indicated on FIGS. 1, 3 and 4 of the drawings, a series of inwardly directed fins or rings 52 are attached to the inner wall of the outer cage 11 and terminate comparatively close to the peripheral wall of the inner cage 12, these fins or rings 52 being placed between successive rows of scoops 29 as will be most clearly seen on FIGS. 1 and 3 of the drawings.

In any event, however, the spacing between the outer surface of the inner cage 12 and the inner wall of the outer cage 11 is kept as small as possible in volume so that the washing medium fed in through the pipe 41 is absorbed to the greatest possible extent by the inner cage 12 where it is applied in contact with the articles under treatment and travelling through the inner cage 12.

Where such fins or rings 52 are provided the positions thereof may coincide with the positions of the division members or radial plates 28 (FIG. 4) dividing the beaters 13 into separate zones. With an arrangement of this type the washing medium cannot flow freely within the outer cage 11 but is forced by the action of the scoops to travel inwardly into the inner cage 12, and the progressive movement of the washing medium is effected mainly by the movement thereof within the inner cage 12 thus maintaining an efficient washing action upon the articles.

As an optional feature, there may be provided at the top of the casing 11 an opening 11a, as suggested in the alternative structure shown in FIGURE 2 of the drawings, for convenient access to the interior of the casing.

What I claim is:

A laundry washing machine comprising a cylindrical outer casing of uniform configuration, a perforated cy-

lindrical inner cage disposed within and co-axially of said casing, both said cage and said casing being inclined to the horizontal, the lengths of said cage and said casing substantially exceeding their respective diameters, 5 means to feed articles to be washed into the upper end of the inner cage, means to remove washed articles from the lower end of the inner cage, means to rotate said inner cage about its longitudinal axis within said outer casing, means to supply washing liquid at the lower end 10 of the outer casing and to extract it from the higher end of said outer casing after traversing the length of said casing, means to provide different operating regimes at different points in the length of said outer casing; and beaters disposed parallel to said longitudinal axis, and 15 extending the whole length of the inner cage to lift the articles simultaneously from the lower zone of the cage along its whole length to a higher position and then to allow them to fall to a lower level position for progression lengthwise of the inner cage by gravity action, each of 20 said beaters comprising a V-shaped perforated portion and an imperforate longitudinally extending web member extending radially inwardly from said inner wall into the apex of said V-shaped portion to divide the space enclosed between said V-shaped portion and said inner wall into two longitudinally extending partial spaces, 25 and partition walls extending radially inwardly from said inner wall into the space enclosed between said V-shaped portion and said inner wall to divide said two partial spaces into a number of compartments said machine furthermore comprising first and second liquid scoops 30 disposed on the outer surface of the inner cage, said first scoops being in communication with the interior of said inner cage, and said second scoops being in communication with said compartments of said beaters, said scoops 35 causing washing liquid to be scooped up during rotation of said inner cage and directed on to articles lifted by said beaters so as to urge said articles away from said beaters and said inner wall and thereby to improve the washing action of the machine, and a series of inwardly directed 40 fin-like baffle members extending circumferentially and radially inwardly from the outer casing towards and nearly into contact with the inner cage between adjacent peripheral rows of said scoops so as to assist in providing separate zones where different operating regimes 45 are maintained and to impede the direct through-flow of washing liquid lengthwise of the machine in the space between said outer casing and said inner cage and to cause said washing liquid to flow in successive paths into and out of the inner cage to maintain an efficient washing 50 action on articles to be treated.
